HANDSET UNIT FOR TIMEPIECES

Walter F. Riemer, Bristol, Conn., assignor to The
E. Ingraham Company, Bristol, Conn., a cor-
poration of Connecticut

Application May 17, 1949, Serial No. 93,677

7 Claims. (Cl. 58—80)

1

The present invention relates in general to timepieces and more especially to the handset of a timepiece and the means for mounting the handset therein, whereby the manually-operable setting-staff of the handset may project radially from the timepiece or from the back thereof.

Heretofore, it has been customary in the manufacture of timepieces, to build the handset into the frame of the timepieces as a permanent part thereof. Consequently, in order to make available to the trade timepieces of the type having the manually-operable setting-staff of the handset projecting from the back of the case and timepieces of the type having the setting-staff of the handset projecting radially from the case, it has been necessary to stock large quantities of the two types of timepieces. The present invention relates to a handset-unit which is so constructed that it may be selectively mounted in a pre-assembled frame of a timepiece so that its setting-staff will project either from the back of the frame or radially thereof, in accordance with a particular requirement.

An object of the invention, therefore, is to provide a superior handset-unit of economical and durable construction.

A further object of the invention is to provide a timepiece with a handset-unit which may be selectively assembled in the frame of the timepiece so that its setting-staff may project from the back of the frame or radially thereof.

A still further object of the invention is to provide a handset-unit for use with a timepiece wherein the pre-assembled movement-plates of the timepiece are provided with two sets of holding-apertures in which the handset-unit is arranged to be selectively assembled so that its setting-staff may project radially from the timepiece or from the back thereof.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a front elevation of the pre-assembled movement-frame of a timepiece showing the handset-unit of this invention mounted therein so that its setting-staff projects radially therefrom;

Fig. 2 is a right-side elevation of the timepiece movement-frame of Fig. 1 but also showing the hour- and minute-hands;

2

Fig. 3 is a fragmentary portion of the back of the movement-frame with the setting-staff of the handset-unit projecting radially therefrom, as in Figs. 1 and 2;

5 Fig. 4 is an enlarged fragmentary plan elevation of the movement-frame and handset-unit on section line 4—4 of Fig. 2;

Fig. 5 is an enlarged fragmentary side elevation partly in section of the movement-frame and 10 handset-unit of Fig. 2;

Fig. 6 is an enlarged fragmentary side elevation of the movement-frame and handset-unit partly 15 in section as in Fig. 5 but showing one movement-plate of the frame deflected outwardly with respect to the opposite movement-plate to permit assembly of the handset-unit in the frame;

Fig. 7 is an enlarged fragmentary side elevation 20 partly in vertical section of the frame of the timepiece showing the handset-unit assembled in the movement-plates so that its setting-staff projects from the back of the frame;

Fig. 8 is a fragmentary enlarged side elevation 25 similar to Fig. 7 but showing one movement-plate deflected outwardly with respect to the opposite movement-plate to permit assembly of the handset-unit in the frame;

Fig. 9 is an enlarged fragmentary rear elevation 30 of the frame of the timepiece on line 9—9 of Fig. 7 showing the handset-unit mounted therein so that its setting-staff projects from the back of the frame;

Fig. 10 is an elevation of the handset-unit of this invention;

Fig. 11 is a perspective view of a fragmentary 35 portion of the front movement-plate showing the handset-unit holding-apertures therein; and

Fig. 12 is an enlarged fragmentary perspective view of the rear movement-plate showing the handset-unit holding-apertures thereof 40 connected by a radial slot intersecting the edge of the movement-plate.

Referring to the drawings, the latter show the pre-assembled movement-frame 15 of a timepiece which may be spring-driven or electrically 45 operated and may or may not include an alarm-mechanism, the pre-assembled movement-frame 15 comprising front and rear movement-plates 16 and 17 respectively held in spaced substantially-parallel relationship by pillars 18. In the 50 embodiment shown, three such pillars are used, each pillar being fixedly secured at one end 19 in the back-plate 17 of the movement-frame and provided at its opposite end with a necked-down portion having external threads 20 for accommodating a nut 21, the front-plate 16 of the move-

ment-frame being adapted to be assembled on the necked-down portions of the pillars 18 and to be held securely against the shoulders thereof by tightening up the nuts 21. By loosening or removing the two nuts 21 adjacent the hereinafter described handset-unit holding-apertures of the movement-frame, the front and back-plates may be sprung apart slightly, as indicated by the broken lines in Fig. 2, to permit assembly of the handset-unit in the movement-frame in the manner and for the purpose described below.

The time-train, energy source and other elements of the timepiece are ancillary to the present invention and consequently are not shown. However, the gear-train with which the handset-unit of this invention is directly associated, is shown and, as indicated generally at 22, comprises, in the main, an hour-sleeve 23 which has a bearing adjacent its inner end in an aperture of the front movement-plate and which projects outwardly therefrom at substantially right angles thereto. Secured to the inner end of the hour-sleeve within the movement-frame 15, is an hour-wheel 24 adapted to mesh with a pinion-gear 25 of the gear-train. The hour-sleeve 23 provides a longitudinal bearing for supporting the minute-arbor 26, the inner end of which extends through the front movement-plate and is journaled in the rear movement-plate of the frame, the portion of the minute-arbor immediately rearwardly of the hour-wheel 24 serving as a support for a pinion-gear 27 which is secured thereto and meshes with a setting-gear 28 of the gear-train. The minute-arbor also serves as a mount for the minute-wheel 29 of the gear-train. As shown in Fig. 2, the hour-hand 30 of the timepiece is secured to the outer end of the hour-sleeve 23, while the minute-hand 31 is secured to the outer end of the minute-arbor 26, the hour-hand 30 and minute-hand 31 being herein-after referred to as the "indicating-means" of the timepiece.

Since the gear-train is of substantially-conventional construction, a more detailed description thereof is deemed to be unnecessary, it being sufficient to point out that it constitutes means for connecting the setting-gear 28 of the gear-train with the indicating-means whereby rotation of the setting-gear 28 will set the hour- and minute-hands respective of the timepiece.

The handset-unit for actuating the setting-gear 28 of the gear-train is indicated generally at 32 and, as shown especially well in Figs. 1, 5 and 10, comprises a setting-member or -staff 33 having a thumb-net 34 secured at its outer end for manually rotating the setting-staff. At its inner end the setting-staff 33 has rigidly secured thereto by a force-fit a setting-pinion 36. Projecting outwardly from the inner end of the setting-staff 33 is a trunnion 37 of reduced diameter. Mounted to rotate freely on the setting-staff 33 rearwardly of the setting-pinion 36 is a bearing-member 38 preferably in the form of a disk provided with an integral concentric collar 39 which is adapted to engage against the inner face of the setting-pinion 36 to hold the bearing-member 38 in spaced relationship thereto, the bearing-member 38 and its spacing-collar 39 being held from sliding longitudinally on the setting-staff 33 away from the setting-pinion 36 by means of a collar 40 which is fixedly secured to the setting-staff 33 and is adapted to bear at its inner end against the adjacent face of the bearing-member 38. The opposite end of the

fixed collar 40 of the setting-staff is reduced in diameter to provide a bearing-sleeve 41.

The aforesaid trunnion 37 and bearing-sleeve 41 constitute, in effect, shouldered bearing-elements 5 of the setting-staff arranged in longitudinally-spaced relationship thereon, these shouldered bearing-elements being hereinafter referred to as a "set of supporting-means" for supporting the handset-unit in the frame of the timepiece in the manner hereinafter described. Likewise, the substantially diametrically-opposite edges 38a and 38b of the rotatable bearing-member 38 constitute a set of supporting-means 10 for supporting the handset-unit in the movement-frame of the timepiece, to which end the diameter of the bearing-member 38 substantially equals the thickness of the movement-frame as and for the purpose hereinafter described.

Complementing the aforesaid sets of supporting-means of the handset-unit are holding-apertures 20 in the respective front and rear movement-plates of the movement-frame. Referring especially to Figs. 11 and 12, the holding-apertures in the front movement-plate comprise an inner substantially-cylindrical bearing-aperture 42 extending therethrough from front to back and of a diameter to receive and support the aforesaid trunnion 37 of the staff 33; and an outer elongated substantially-rectangular holding-slot 25 43. The latter extends through the movement-plate from front to back between the bearing-aperture 42 and the outer edge 44 of the plate 16 and is adapted to receive and support one 30 of the aforesaid edges 38a—38b of the bearing-member 38 of the handset-unit. In this connection, the length of the holding-slot 43 is less than the diameter of the aforesaid bearing-member or disk 38, whereby either of the diametrically-opposite edges 38a—38b of the disk 35 are effectively held from passing through the holding-slot 43 of the frame. Moreover, the longitudinal axis of the holding-slot 43 is at substantially right-angles to and bisected by a radial line 40 extending from the center of the movement-plate through the center of the bearing-aperture 42, and consequently, in conjunction with a similar holding-slot of the rear movement-plate, serves to hold the bearing-member 38 in a plane 45 at substantially right angles to the aforesaid radial line of the movement-plate 16 and in a plane perpendicular to the plane thereof.

The holding-apertures in the rear movement-plate 17 are substantially in alignment with the corresponding holding-apertures of the front movement-plate and comprise an inner cylindrical bearing-aperture 45 extending through the rear movement-plate from front to back and substantially opposite the bearing-aperture 42 of the front movement-plate 16, the diameter of the bearing-aperture 45 corresponding substantially to the diameter of the bearing-sleeve 41 of the setting-staff 33 for rotatably supporting the latter. Formed between the bearing-aperture 45 and the outer edge 46 of the rear movement-plate 17 is an outer elongated substantially-rectangular holding-slot 47 of substantially the same size, configuration and orientation as the holding-slot 43 of the front movement-plate, the holding-slot 47 being adapted to accommodate one of the diametrically-opposite edges 38a—38b of the bearing-member 38 to support the latter in the frame in the manner hereinabove described.

The substantially-similar cylindrical bearing-apertures 42 and 45 of the front and rear move-

ment-plates respectively constitute a set of holding-apertures for receiving the aforesaid set of supporting-means 37 and 41 respectively of the setting-staff 33, while the substantially-similar rectangular slots 43 and 47 of the front and rear movement-plates respectively likewise constitute a set of holding-slots for receiving the aforesaid set of supporting-means 38a and 38b respectively of the bearing-member 38.

Extending outwardly substantially radially from the bearing-aperture 45 of the rear movement-plate to the outer edge 46 thereof, is a radial clearance-slot 48 which connects the bearing-aperture 45 and its respective holding-slot 47, the radial interconnecting clearance-slot 48 being coextensive of and substantially-symmetrical with respect to a radial line extending through the bearing-aperture 45 and the holding-slot 47. The width of the aforesaid radial clearance-slot 48 is less than the diameter of the bearing-aperture 45 and corresponds substantially to the diameter of the setting-staff 33 of the handset-unit and hence provides, in effect, restricting-shoulders 48a—48b at its point of intersection with the bearing-aperture 45, the shoulders 48a—48b being adapted to positively hold the bearing-sleeve 41 of the handset-unit from moving upwardly out of its holding-aperture 45 into the interconnecting clearance-slot 48.

The handset-unit is adapted to be assembled in the movement-frame as follows. A pre-assembled movement-frame such as shown in Figs. 1 and 2 is taken from stock and the two nuts 21 of the pillars 18 nearest the handset-unit holding-apertures of the front movement-plate 16 are removed, as indicated in Fig. 2, or sufficiently loosened, whereby the front and rear movement-plates may be spread apart slightly, as indicated by the broken lines in Fig. 2 and by the full lines in Fig. 6. Assuming that the pre-assembled movement-frame is to be provided with a handset-unit, the setting-staff of which is to project radially from the frame, as indicated in Figs. 1 through 6, then the handset-unit 32 is inserted between the spread-apart movement-plates of the frame so as to engage the outer edges 38a and 38b of its bearing-member 38 in the said outer holding-slots 43 and 47 respectively of the corresponding movement-plates. Thereupon, the movement-plates are free to spring back to their normal substantially spaced-parallel relationship in which relationship they are securely held by tightening up the beforementioned nuts 21 on the corresponding pillars of the frame. Since the diameter of the bearing-member 38 exceeds the length of each slot, only the outer edges 38a and 38b of the bearing-member project through the slots, whereby the bearing-member is held securely from lateral displacement in the frame. Moreover, since the height of each slot corresponds substantially to the thickness of the bearing-member, the latter is held from radial displacement with respect to the movement-frame. With the bearing-member 38 of the handset-unit secured in the outer holding-slots of the frame, as hereinabove described, the setting-staff of the handset-unit will be supported substantially radially with respect to the movement-frame, the setting-pinion on the inner end of the staff being in endwise mesh with the setting-gear 28 of the gear-train, whereby rotation of the thumb-nut on the outer end of the setting-staff will rotate the setting-gear 28 of the gear-train to set the hour- and minute-hands of the timepiece.

Should it be desired to assemble a handset-unit

in a movement-frame so that the setting-staff 33 will project substantially perpendicularly from the back-face thereof, as shown in Figs. 7, 8 and 9, then the assembly-nuts 21 of the movement-frame are loosened or removed to permit the movement-plates to be sprung apart, as indicated in Fig. 8. Thereupon, the shouldered bearing-element or trunnion 37 of the setting-staff is engaged in its respective bearing-aperture 42 of the front movement-plate, and the staff of the handset-unit swung down about its bearing-trunnion 37 as a pivot into the radial clearance-slot 48 of the rear movement-plate 17, the width of the aforesaid radial clearance-slot 48 being such as to accommodate the setting-staff 33.

As has been pointed out above, the bearing-sleeve 41 of the setting-staff is of greater diameter than the width of the radial clearance-slot 48 and consequently the bearing-sleeve 41 will not enter into the clearance-slot but will engage the edges thereof on the inner face of the rear movement-plate, as indicated in Fig. 8, thereby holding the movement-plates spread apart until the bearing-sleeve 41 is opposite its bearing-aperture 45 in the rear movement-plate. Thereupon, the bearing-sleeve 41 may enter its bearing-aperture 45 of the rear movement-plate. When this occurs, the setting-staff 33 of the handset-unit extends at substantially right angles to the plane of the movement-plates, with the thumb-nut of the setting-staff projecting from the back of the movement-frame. With the bearing-elements 37 and 41 of the handset-unit assembled in their respective set of bearing-apertures 42 and 45 of the movement-plates, the latter may be pulled together by tightening the aforementioned nuts 21 of the pillars 18 to hold the plates in fixed spaced-parallel relationship. With the setting-staff of the handset-unit assembled thusly in the frame of the timepiece, the setting-pinion of the staff peripherally meshes with the setting-gear of the gear-train, whereby manual operation of the thumb-nut of the handset-unit actuates the gear-train to set the hour- and minute-hands of the timepiece. Since the width of the radial clearance-slot 48 is less than the diameter of the bearing-sleeve 41 of the staff, the bearing-sleeve is positively held by the shoulders 48a and 48b of the slot from moving upwardly therein. Moreover, as so assembled in the frame, the shoulder of the trunnion 37 engages the inner face of the front movement-plate, while the shoulder of the bearing-sleeve 41 engages the inner face of the rear movement-plate, as a consequence of which the setting-staff is effectively held from lateral displacement in the movement-frame.

Thus, it is possible by means of the improved handset-unit of this invention and the respective sets of holding-apertures formed in the movement-plates of the timepiece to assemble a handset-unit in a pre-assembled movement-frame so that the setting-staff will project radially from the frame or project from the back thereof, depending upon the particular requirements of the trade. Consequently, a relatively-small stock of pre-assembled movement-frames may be kept on hand and any one frame adapted to a particular requirement by assembling a handset-unit therein in either of the manners hereinabove described.

The invention may be carried out in other specific ways than those herein set forth without departing from the spirit and essential characteristics of the invention, and the present em-

bodiments are, therefore, to be considered in all respects as illustrative and not restrictive, and all changes coming within the meaning and equivalency range of the appended claims are intended to be embraced therein.

I claim:

1. In a timepiece, the combination including: a movement-frame comprising substantially spaced-parallel front and rear movement-plates, each plate having a pair of holding-apertures formed therein, the pair of holding-apertures of one movement-plate being interconnected by a clearance-slot which intersects the periphery of said one movement-plate, and similar holding-apertures of said front and rear movement-plates respectively constituting two sets of holding-apertures; time-indicating means; a setting-gear assembled between said front and rear movement-plates; means operatively connecting the said setting-gear to the said time-indicating means; and a handset-unit, said handset-unit having two sets of supporting-means for selectively assembling said handset-unit in either of two positions in said movement-frame, one of said sets of supporting-means being arranged to engage in one of the sets of holding-apertures of said movement-plates to support said handset-unit substantially radially of said movement-frame and in cooperative engagement with said setting-gear, and the second set of supporting-means being arranged to be engaged in the second set of holding-apertures of said movement-plates by the clearance afforded by the said interconnecting clearance-slot to support said handset-unit substantially perpendicularly to said movement-frame and in cooperative engagement with said setting-gear.

2. In a timepiece, the combination including: a movement-frame comprising substantially spaced-parallel front and rear movement-plates, each plate having a pair of holding-apertures formed therein, the pair of holding-apertures of one movement-plate being interconnected by a clearance-slot which intersects the periphery of said one movement-plate, and similar holding-apertures of said front and rear movement-plates respectively constituting two sets of holding-apertures; time-indicating means; a setting-gear assembled between said front and rear movement-plates; means operatively connecting the said setting-gear to the said time-indicating means; and a handset-unit, said handset-unit having two sets of supporting-means oriented in planes at substantially right angles to each other for selectively assembling said handset-unit in either of two positions in said movement-frame, one of said sets of supporting-means being arranged to engage in one of the sets of holding-apertures of said movement-plates to support said handset-unit substantially radially of said movement-frame and in cooperative engagement with said setting-gear, and the second set of supporting-means being arranged to be engaged in the second set of holding-apertures of said movement-plates by the clearance afforded by the said interconnecting clearance-slot to support said handset-unit substantially perpendicularly to said movement-frame and in cooperative engagement with said setting-gear.

3. In a timepiece, the combination including: a movement-frame comprising substantially spaced-parallel front and rear movement-plates, each plate having a pair of holding-apertures formed therein, the pair of holding-apertures of

one movement-plate being interconnected by a clearance-slot which intersects the periphery of said one movement-plate, and similar holding-apertures of said front and rear movement-plates respectively constituting two sets of holding-apertures; time-indicating means; a setting-gear assembled between said front and rear movement-plates; means operatively connecting the said gear-wheel to the said time-indicating means; and a handset-unit, said handset-unit having two sets of supporting-means, one of said sets of supporting-means being rotatable with respect to said handset-unit and oriented in a plane at substantially right angles to the other set of supporting-means, the two sets of supporting-means being arranged to selectively assemble said handset-unit in either of two positions in said movement-frame, one of said sets of supporting-means being arranged to engage in one of the sets of holding-apertures of said movement-plates to support said handset-unit substantially radially of said movement-frame and in cooperative engagement with said setting-gear, and the second set of supporting-means being arranged to be engaged in the second set of holding-apertures of said movement-plates by the clearance afforded by the said interconnecting clearance-slot to support said handset-unit substantially perpendicularly to said movement-frame and in cooperative engagement with said setting-gear.

4. In a timepiece, the combination including: a movement-frame comprising substantially spaced-parallel front and rear movement-plates, each plate having a pair of holding-apertures formed therein comprising a bearing-aperture and a longitudinal slot, the bearing-aperture and longitudinal slot of one plate being interconnected by a radial clearance-slot which intersects the periphery of said one plate, the similar holding-apertures of said front and rear movement-plates respectively constituting two sets of holding-apertures; time-indicating means; a setting-gear assembled between said front and rear movement-plates; means operatively connecting the said setting-gear to the said time-indicating means; and a handset-unit comprising a bearing-member and a manually-operable setting-member mounted for rotation in the said bearing-member and having a setting-pinion, the said setting-unit having two sets of supporting-means for selectively assembling said handset-unit in either of two positions in said movement-frame, one of said sets of supporting-means being arranged to be engaged in the set of bearing-apertures of said movement-plates by the clearance afforded by the said clearance-slot to support the said manually-operable setting-member substantially perpendicularly to said movement-frame with said setting-pinion in peripheral mesh with said setting-gear, and the second set of supporting-means being arranged to engage in the set of longitudinal slots of said movement-plates to support the said manually-operable setting-member substantially radially of said movement-frame with said setting-pinion in endwise mesh with said setting-gear.

5. In a timepiece, the combination including: a movement-frame comprising substantially spaced-parallel front and rear movement-plates, each plate having a pair of holding-apertures formed therein, comprising a bearing-aperture and a longitudinal slot, the bearing-aperture and longitudinal slot of one plate being intercon-

nected by a radial clearance-slot which intersects the periphery of said one plate, the similar holding-apertures of said front and rear movement-plates respectively constituting two sets of holding-apertures; time-indicating means; a setting-gear assembled between said front and rear movement-plates; means operatively connecting the said setting-gear to the said time-indicating means; and a handset-unit comprising a bearing-member and a manually-operable setting-member mounted for rotation in the said bearing-member and having a setting-pinion, the said setting-unit having two sets of supporting-means for selectively assembling said handset-unit in either of two positions in said movement-frame, one of said sets of supporting-means comprising bearing-elements on said manually-operable setting-member arranged to be rotatably engaged in the set of bearing-apertures of said movement-plates by the clearance afforded by the said interconnecting clearance-slot of one plate to rotatably support the said manually-operable setting-member substantially perpendicular to said movement-frame with said setting-pinion in peripheral mesh with said setting-gear, and the second set of supporting-means comprising the substantially oppositely-disposed edges of said bearing-member which are arranged to engage in the set of longitudinal slots of said movement-plates to support the said manually-operable setting-member substantially radially of said movement-frame with said setting-pinion in endwise mesh with said setting-gear.

6. In a timepiece, the combination including: a movement-frame comprising substantially spaced-parallel front and rear movement-plates, each plate having an outer holding-aperture and an inner holding-aperture formed therein, the inner holding-aperture comprising a bearing-aperture and the outer holding-aperture comprising a longitudinal slot, the bearing-aperture and longitudinal slot of one plate being interconnected by a radial clearance-slot which intersects the periphery of said one plate, the similar holding-apertures of said front and rear movement-plates respectively constituting two sets of holding-apertures; time-indicating means; a setting-gear assembled between said front and rear movement-plates; means operatively connecting the said setting-gear to the said time-indicating means; and a handset-unit comprising a bearing-member and a manually-operable setting-member mounted for rotation in the said bearing-member and having a setting-pinion, the said setting-unit having two sets of supporting-means for selectively assembling said handset-unit in either of two positions in said movement-frame, one of said sets of supporting-means comprising shouldered bearing-elements on said manually-operable setting-member on opposite sides respectively of its bearing-mem-

ber, said shouldered bearing-elements being arranged to be rotatably engaged in the set of inner bearing-apertures of said movement-plates by the clearance afforded by the said interconnecting clearance-slot of one plate, to rotatably support the said manually-operable setting-member substantially perpendicular to said movement-frame with said setting-pinion in peripheral mesh with said setting-gear, the shoulders of said shouldered bearing-elements being arranged to cooperatively engage corresponding movement-plates of said movement-frame to prevent displacement of the said manually-operable setting-member transversely of said movement-frame, and the second set of supporting-means comprising the substantially oppositely-disposed edges of said bearing-member which are arranged to engage in the set of outer longitudinal slots of said movement-plates to support the said manually-operable setting-member substantially radially of said movement-frame with said setting-pinion in endwise mesh with said setting-gear.

7. In a timepiece, the combination including: a movement-frame comprising a first movement-plate having an inner holding-aperture and an outer holding-aperture therein, a second movement-plate laterally spaced from the said first movement-plate in substantial parallelism therewith and also having an inner holding-aperture and an outer holding-aperture respectively in substantial alignment with the similar holding-apertures of the said first movement-plate and also having a clearance-passage connecting the said inner holding-aperture with the said outer holding-aperture and connecting the latter with the edge of the said second movement-plate; time-indicating means carried by the said movement-frame; a gear-wheel located between the two said movement-plates; means operatively connecting the said gear-wheel to the said time-indicating means; and a handset-unit comprising a bearing-member and a manually-operable setting-member mounted for rotation in the said bearing-member and having a setting-gear, the said setting-unit having a first pair of supporting-means respectively engageable in two similar supporting-apertures respectively in the said movement-plates and constructed and arranged to hold the said setting-gear in endwise mesh with the aforesaid gear-wheel, the said handset-unit also having a second pair of supporting-means engageable in the other two supporting-apertures respectively in the said movement-plates and constructed and arranged to hold the said setting-gear in peripheral mesh with the aforesaid gear-wheel; whereby the said handset-unit may be interchangeably connected with the said movement-frame in either of two operative relationships.

WALTER F. RIEMER.
